(57) **CLAIM**

The ornamental design for a soap container, as shown and described.

DESCRIPTION

FIG. 1 is a top perspective view of a soap container showing my new design;

FIG. 2 is a bottom perspective view thereof;

FIG. 3 is a top exploded view thereof;

FIG. 4 is a bottom exploded view thereof;

FIG. 5 is a front elevation view thereof, a rear elevation view being a mirror image thereof;

FIG. 6 is a right side elevation view thereof, a left side elevation view being a mirror image thereof;

FIG. 7 is a top plan view thereof;

FIG. 8 is a bottom plan view thereof;

FIG. 9 is a front exploded view thereof, showing the plane upon which a cross-sectional view is taken and shown in FIG. 10;

FIG. 10 is a cross sectional view thereof, taken along line 10-10 of FIG. 9;

FIG. 11 is a right side exploded view thereof, showing the plane upon which a cross-sectional view is taken and shown in FIG. 12; and,

FIG. 12 is a cross section view thereof, taken along line 12-12 of FIG. 11.

The broken line showing of a logo in FIG. 7 is included for the purpose of illustrating environmental structure and forms no part of the claimed design.

1 Claim, 12 Drawing Sheets
